John Ward
Letters Patent

The Schedule referred to in these Letters Patent and making part of the same containing a description in the words of the said William Ward himself of his improvement in the mode of marking out cloth for cutting into clothing by means of Scales & Protractors & Scale.

To cut out a coat by my system, I first make a protractor about 16 inches diameter, and divide the semicircle of the Protractor in to fifty equal parts, with the angle of the protractor placed from me, I begin on the left and number the degrees, with the number one in the first degree, 2 in the second, 3 in the third, and so increase the numbers agreeably to the lines, which lines must be previously run from the middle of the straight edge of the protractor. To 23 will from a right angle with the straight edge of the protractor. I next proceed to make a scale the semi-circumference of my vestment, body taken close under his arms divided into 32 equal parts, and these parts numbered beginning at the left hand end of the scale with No. 1. on the first line, No. 2. on the second, and so continue the figures upon the parts, until all the parts are numbered, which constitutes a scale suitable for the thickness round the breast, & make one scale at so far the waist in like manner having taken the length of the coat. I spread my cloth the nap running to my left. I apply the protractor and square my cloth by an angle of 23 degrees, beginning at the right hand end of my cloth, which is generally termed the top of the cloth, from the nap corner of which I run an angle of 2 degrees, which represents the back seam of the coat, from the upper corner I run down to the said seam, or angle one and a half of the scale and make a mark or said angle a back seam, from said mark I run down six and a half and make a mark, from which I run across at right angles with the back seam, eleven of the scale, this will give the top

of the back sigh, and the breadth of the back between the shoulder seams, from two and a half on the back line I proceed threewand a half down, and run another right line at an angle of twenty-five degrees, and run out on said line from the back seam of 11 which will give the bottom and length of the back sigh. The length of the waist being ascertained by the measure I run a line across the nape of the cloth, sufficient for the breadth of the skirt, my 6 inches from the intersection of the back seam I run out on said line three and a half on the scale, which gives the width of the back between the buttons, and one inch and a half for the skirt in the square at the top of the cloth I run across 3, which will give the width of the top of the back, from which place I take a sweep of 30. of the scale to the top of the back sigh, which sweep represents the shoulder seam. I also take a sweep of 30 from the top to the bottom of the back sigh which covers the back sigh. I also take a sweep of 30 from 3 at the top of the back to one and a half at the back seam which will cover the top of the back.

I also take a sweep of two lengths of the side seam from the bottom of the back sigh to the width of the back at the hip between the buttons, which sweep represents the side seam of the back. The back skirt is cut agreeably to the back, thus completes the marking of the back of a coat for the present fashion. I next mark out the free parts of the coat. First I run a line from the top of my cloth to the length of the coat parallel with and one and a half inch from the far and double edge of the cloth, which line is termed the plait line of square said line at the top of my cloth, and run down said line five and a half, from thence down said line six and a half, from thence down said line threewand one fourth, from five and a half I run an angle of sixteen and a half degrees the intersection of which angle with the square line at the top of the cloth will from the top of the shoulder seam, from thence

I run down said seam low which will give the front of the shoulder seam. I next run an angle from six and a half on the plait line of 20 degrees. I come out on said angle nine and three fourths to find the front of the sigh, from thence I continue along said angle fourteen to find the top of the breast. I then run another angle from three and a fourth on the plait line by 23 of the protractor which is a right angle with my scale. I commence at the plait line and mark one on the far side of said line from which I take a sweep of six, to the side and a half on the plait line, which sweep will touch the top of the side seam, from said three and a fourth on said plait line, I run six in on the angle of 23 degrees, which sweep will give the bottom of the sigh. From thence I continue 21 on said angle to find the front of the breast, from which point I take a sweep of 18 to the top of the breast, from thence I take a sweep of fifteen to the top of the shoulder seam which forms the yoke, from the point of the shoulder seam to the front of the sigh, I take a sweep of four to form the upper part of the sigh, from said nine and three fourths on front of the sigh, to the bottom of the sigh, I take a sweep of four and one fourth, which forms the under part of the sigh, from the said bottom of sigh to six and a half on the plait line. I take a sweep of six which forms the hind part of the sigh and the top of the side seam, from which top I run down the plait line the length of the back side seam to find the hips, and from thence to the bottom of the coat, from the hip I run an angle of twenty one and a half degrees, which forms the flap line. I run along said line 20 numbers of a scale corresponding with the waist measure and from said twenty, I proceed nine further to the front of the waist from which I take a sweep thirty two to come the front of the breast below, from twenty one and flap line I run an angle of 32, by which out the skirt, an angle of 14 is to be run from the length of the breast, on the skirt line which will form the bottom of the

breast. That the coat may have spring in the hip. I cut off the bottom of the side seam half an inch, more or less, cutting the coat across to go on the flap line, taking a sweep of 32^{1/2} from said 20. to the hip; which sweep will cut the cloth bias and curving above, the flap line, after which I cut off one number off the width of bottom of the side seam, and when joining the curved and flap lines together the curved line must be held out to the flap line. The capel must be cut separate and scanned to the breast agreeably to taste; to form a sleeve of round straight line, down the near edge of the cloth. I square said line at the top, & run down two on the breast scale, from which two I run an angle of nineteen degrees, for the width of the sleeve head. I run out on said angle fifteen, and to form the sleeve head I take a sweep of eight and a half, from two on the straight line to fifteen on the angle from the elbow of the sleeve, then an angle of five degrees to crook the sleeve by, and then cut the size and length of my sleeve, by the customers measure; for crooked or straight men I run the angles differently to it; for a straight man I run the angles higher than described and for a crooked man lower. This adds to diminish the number according to his size, that the neck may be regulated.
